HUMIDIFYING DEVICE

Application filed November 28, 1930. Serial No. 498,629.

This invention relates to an auxiliary heater and an auxiliary humidifying device adapted to be used in connection with a furnace. While the device is applicable for use with various types of furnaces, it particularly is designed for use in connection with an oil burning furnace. There is often insufficient radiating surface to properly use the heat generated in an oil burner, and undesirable stack temperatures often result. It is desirable to have the air supplied to living rooms at a certain degree of humidity, and the importance of this is emphasized today by heating engineers.

It is an object of this invention to provide a simple and efficient device for receiving the products of combustion from a furnace, using the heat thereof to heat air which is supplied to living rooms and at the same time supply humidity to said air.

It is another object of the invention to provide a device comprising a casing containing a water pan or receptacle, means for directing air over the water means for heating said air from the products of combustion of the furnace, said device having a chamber into which said air is delivered, and from which conduits lead to the rooms to be supplied with heated air.

It is more specifically an object of the invention to provide a device comprising a casing, a water container in said casing, a plurality of spaced conduits having open ends one of which is disposed adjacent the water in said container, said conduits communicating with a common chamber in said casing, a pair of conduits communicating with said device at opposite sides, and adapted to be connected respectively to the smoke pipe of a furnace and to the chimney, the gases passing through said last mentioned conduits passing around said water container to heat the water therein and the air passing through said first mentioned conduits.

These and other objects and advantages of the invention will be fully set forth in the following description made in connection with the accompanying drawing, in which like reference characters refer to similar parts throughout the several views, and in which:—

Fig. 1 is a perspective view of the device, certain parts being broken away to show the interior thereof;

Fig. 2 is a vertical section taken on line 2—2 of Fig. 3;

Figure 3 is a horizontal section taken on line 3—3 of Fig. 2; and

Fig. 4 is a vertical section taken on line 4—4 of Fig. 3.

Referring to the drawing, a device is shown comprising a casing 10. While this casing might be made of various forms, in the embodiment of the invention illustrated it is shown as of rectangular form and elongated. A conduit 11 communicates with the bottom of casing 10 centrally thereof, said conduit having a flange 11a secured to the bottom of casing 10. Casing 10 has a pair of spaced partitions 10a secured to its ends, the same shown as having out-turned flanges at their ends secured to the ends of casing 10. These partitions 10a are connected at their bottom by a plate 10c, the plates 10a and 10c thus forming three sides of a rectangular casing, and the plate 10b extends between plates 10a a short distance below their top edges, this plate extending to the ends of casing 10. A rectangular casing 12 extends downward from the central portion of plate 10b, said casing 12 being adapted to form a water receptacle, and the water may also be contained in the pan formed between the plates or partitions 10a and the ends of casing 10, the water being represented in Fig. 4 as 12a. The plates 10a, 10b and 10c form a rectangular casing disposed within casing 10. It is desired to maintain a certain level of water in casing 12 and the pan thereabove. While a suitable means may be used for maintaining such level, in the embodiment of the invention illustrated a float 13 is used, secured to a lever 14 pivoted at 16 to a valve and bracket 17 secured to a pipe 18 extending through the end of casing 12 and through the end of casing 10. This pipe will be secured to the end of casing 10 by a suitable coupling 19. A motor 20 illustrated as of the electrical type is mounted upon a suitable supporting means such as the legs 21, which will rest upon the floor or other supporting surface.

Motor 20 has a fan 22 secured to its shaft which is located axially below the conduit 11 as shown in Fig. 2. The partitions 10a form vertically extending passages 24 between the same, and the sides of the casing 10, and a chamber is formed below the top of casing 10. A conduit 27 extends through the side of casing 10 and communicates with the interior of the casing formed by plates 10a, 10b and 10c through an opening in one of the plates 10a, said conduit having an out-turned flange secured to said plate 10a. Another conduit 28 has an out-turned flange secured to the other partition 10a and also communicates with the chamber between plates 10a through an opening in the plate 10a to which it is secured. Casing 12 has a conduit 12b extending between its sides, said conduit being axially alined with the conduits 27 and 28 and being controlled by a damper member 25 secured to a rod 25a having a crank on its end which in turn is pivotally secured to a handle rod 26 extending through a tube 26a secured in one plate 10a and one side of the casing 10. Rod 26 has a ring 26b at its outer end and tube 26a is provided with a packing nut 26c at its outer end. It will be seen that damper 25 can be regulated by the rod 26. The conduit 27 is adapted to be connected to the smoke pipe 29a of a furnace 29 and the conduit 28 is adapted to be connected to a chimney 30. A conduit 31 has an out-turned flange 31a secured to the top of casing 10 and communicates with the interior of the casing 10 through an opening in the top thereof, conduit 31 preferably being axially alined with conduit 11.

In operation the conduit 31 will extend to one or more rooms to be heated, and motor 20 will be driven. Air will be forced into conduit 11 and this air will be deflected by the plate 10c and will pass around the partitions 10a and into the chamber at the top of casing 10 over the water in the pan at the top of casing 12 and out through the conduit 31 as indicated by the arrows 32. The hot products of combustion from furnace 29 will pass through conduit 27 and the same will pass around the bottom and ends of casing 12 as indicated by the arrows 32 and will then pass out through conduit 28 to the chimney. The casing 12 will be heated as will the water therein, and the plates 10a and 10c will also be heated. Part of the water will be evaporated and will pass out with the air passing through conduit 31. This evaporation will be assisted by the air passing up around the plates 10a and over the top of the water, so that the air passing out through conduit 31 is well humidified. The air passing in through conduit 11 will also be heated by its passage around the plates 10c and 10a so that warm humidified air is supplied to the rooms through conduit 31. The desired level of water will be maintained by the float 13 reg-

ulating the valve 17. If a stronger or more direct draft is desired through the device, the damper 25 can be opened by manipulating the operating rod 26. If this is done, the products of combustion can pass directly through the conduit 12b and will not have to pass around casing 12. The damper 25 will normally be closed.

From the above description it is seen that applicant has provided a very simple heating and humidifying device. The excess heat in the products of combustion from the furnace is utilized to heat the air which is delivered to the rooms to be heated, and to evaporate water to supply the desired humidity. The apparatus is quite efficient, as it uses only heat which would otherwise pass into the chimney and be lost. The device is simple in construction, can be inexpensively made and installed, and results in quite a saving of fuel. The device has been amply demonstrated in actual practice and found to be very successful and efficient.

It will, of course, be understood that various changes may be made in the form, details, arrangement and proportions of the parts, without departing from the scope of applicant's invention, which, generally stated, consists in a device capable of carrying out the objects above set forth, in the parts and combinations of parts disclosed and defined in the appended claims.

What is claimed is:—

1. A heating and humidifying device adapted to be used in connection with a furnace having in combination, a closed casing, a water pan at the upper end of said casing, closed casing having a chamber therein within said casing, an inlet conduit connected to one side of said chamber adapted to be connected to the smoke pipe of the furnace, an outlet conduit at the opposite side of said chamber adapted to be connected to a chimney, said pan having an extension disposed in said chamber, the gases passing through said inlet and outlet conduits passing around said extension and inlet and outlet conduits for air in said casing respectively below and above said pan.

2. A heating and humidifying device adapted to be used in connection with a furnace having in combination, a casing, a water container in said casing, passages for air extending upwardly through said casing at the sides of said container, a conduit leading into the bottom of said casing having an open lower end, a fan for directing air into said open end, a motor for driving said fan, a conduit leading from the top of said casing, a casing in said casing and spaced from the walls thereof, and conduits leading into and out of the sides of said last mentioned casing for conveying the products of combustion from said furnace therethrough, said

water container forming the top of said last mentioned casing.

3. A heating and humidifying device adapted to be used in connection with a furnace having in combination, a casing, a water container in said casing, a plurality of passages for air extending upwardly through said casing, at the sides of said container, a chamber at the top of said casing with which said passages communicate, a conduit leading from the top of said casing and from said chamber to the rooms to be heated and humidified, a casing within said first mentioned casing and below said container, conduits leading into and out of the sides respectively of said last mentioned casing for conveying the products of combustion from said furnace, a conduit at the bottom of said casing having an open lower end disposed adjacent the floor, and means for directing air into said open end for movement through said passages and over said container.

4. A heating and humidifying device comprising a casing, a fresh air conduit communicating with the bottom of said casing, a conduit leading from the top of said casing and adapted to be connected to the rooms to be supplied with heat, a second closed casing within said casing and spaced from the walls thereof, a water container in said second casing, a conduit leading from a furnace and communicating with said second casing, and a conduit leading from said second casing opposite said last mentioned conduit adapted to be connected to a chimney, said water container being disposed between said two last mentioned conduits whereby said second casing and water container will be heated and the air passing around said second casing will also be heated.

5. A heating and humidifying device having in combination, a casing, means for supplying fresh air to the bottom of said casing, a conduit leading from the top of said casing to the rooms to be heated, a second casing within and spaced from the walls of said first mentioned casing, a water container extending vertically between the sides of said second casing, a conduit connected to said second casing and leading to the smoke pipe of a furnace, a conduit connected to the opposite side of said second casing and leading to a chimney whereby the products of combustion must pass around said water container, said water container having a passage therethrough in line with said last mentioned conduits, and means for opening and closing said passage.

6. A heating and humidifying device adapted to be used in connection with a furnace having in combination, a casing, a second casing within and spaced from the walls of said casing, a conduit adapted to be connected to said furnace to receive the products

of combustion therefrom leading into said second casing, a conduit leading from the opposite side of said second casing adapted to be connected to a chimney, a member containing water extending transversely of said second casing and disposed substantially between said conduits, a water pan at the upper portion of said first mentioned casing, an inlet for air adjacent the bottom of said first mentioned casing, an outlet leading from the top of said first mentioned casing whereby air entering said inlet will pass about said second casing and over said water pan to said outlet.

7. A heating and humidifying device adapted to be used in connection with a furnace having in combination, a substantially closed casing, a second substantially closed casing within and spaced from the walls of said first mentioned casing, a water pan above said second casing and adjacent the top of said first mentioned casing, an air inlet adjacent the bottom of said first mentioned casing, an outlet for air at the top of said first mentioned casing whereby air entering said inlet can pass beneath and around the sides of said second casing and over said pan to said outlet, a conduit leading through the side of said first mentioned casing and communicating with said second casing adapted to be connected to the smoke pipe of a furnace, a conduit leading from the opposite side of said second casing through the side of said first casing and adapted to be connected to a chimney, and means extending from said water pan downwardly into said second casing between said last two conduits whereby the products of combustion passing through said latter conduits must pass around said means.

8. A heating and humidifying device adapted to be used in connection with a furnace having in combination, a substantially closed casing, a second substantially closed casing within and spaced from the walls of said first mentioned casing, a water pan above said second casing and adjacent the top of said first mentioned casing, an air inlet adjacent the bottom of said first mentioned casing, an outlet for air at the top of said first mentioned casing whereby air entering said inlet can pass beneath and around the sides of said second casing and over said pan to said outlet, a conduit leading through the side of said first mentioned casing and communicating with said second casing adapted to be connected to the smoke pipe of a furnace, a conduit leading from the opposite side of said second casing through the side of said first casing and adapted to be connected to a chimney, and means disposed in said second casing between said latter conduits including a water containing means about which the products of combustion must pass in passing from said first mentioned conduit to said second mentioned conduit, whereby

the water in said water containing means will be heated.

9. A heating and humidifying device adapted to be used in connection with a furnace having in combination, a casing substantially rectangular in vertical and horizontal cross section, a second casing within and spaced from the walls of said casing, a conduit adapted to be connected to said furnace to receive the products of combustion therefrom leading into said second casing, a conduit leading from the opposite side of said second casing adapted to be connected to a chimney, a member extending downward from the top of said second casing between said conduits having an opening therein, a swinging valve in said opening, a water pan at the upper portion of said first mentioned casing and at the top of said second mentioned casing at the exterior thereof, an inlet for air adjacent the bottom of said first mentioned casing, an outlet leading from the top of said first mentioned casing whereby air entering said inlet will pass around said second casing and over said water pan to said outlet.

10. A heating and humidifying device adapted to be used in connection with a furnace having in combination, a casing substantially rectangular in horizontal and vertical cross section, a second casing within and having its walls substantially parallel to and spaced from the walls of said casing, a conduit connected to said furnace to receive the products of combustion therefrom and leading from one side of said second casing, a conduit leading from the opposite side of said second casing adapted to be connected to a chimney, a water pan disposed in said first mentioned casing and disposed at the top and exterior of said second mentioned casing and extending across the same, an inlet for air adjacent the bottom of said first mentioned casing, a conduit leading from the top of said first mentioned casing whereby air entering said inlet will pass around said second casing over said water pan and out of said conduit at the top of said first mentioned casing.
